[57] CLAIM

The ornamental design for a neurological testing device, as shown and described.

DESCRIPTION

FIG. 1 is a perspective view showing the top and right side elevational view of the neurological testing device;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a perspective view similar to FIG. 1 with a filament in the operative position for testing a person's sensation.
